MOUNTING PLATE FOR MOP HEADS

Hugh Murphy, Hockering, Woking, Surrey, England, assignor to The Prestige Group Limited, London, England, a company of Great Britain

Filed Apr. 20, 1962, Ser. No. 69,785

Claims priority, application Great Britain Nov. 23, 1961

Term of patent 14 years

(Cl. D9—2)

FIG. 3

FIG. 5

FIG. 1 is a top perspective view of a mounting plate for mop heads, showing my new design.

FIG. 2 is a rear elevational view thereof.

FIG. 3 is an end elevational view thereof taken from the left of FIG. 1.

FIG. 4 is a bottom plan view thereof.

FIG. 5 is a cross-sectional view taken along line 5—5 of FIG. 4.

I claim:

The ornamental design for a mounting plate for mop heads, as shown.
